UNITED STATES PATENT OFFICE.

HARRY A. SPURGEON, ALVIN T. HUNT, AND WILLIAM G. BAKER, OF INDIANAPOLIS,
INDIANA.

RULE-HOLDING SLUG-FORM FOR LINOTYPE-MACHINES AND PROCESS OF PRODUCING SAME.

1,139,593.

Specification of Letters Patent.

Patented May 18, 1915.

Application filed May 21, 1913, Serial No. 769,100. Renewed January 25, 1915, Serial No. 4,401.

To all whom it may concern:

Be it known that we, HARRY A. SPURGEON, ALVIN T. HUNT, and WILLIAM G. BAKER, citizens of the United States, residing at 5 Indianapolis, Marion county, and State of Indiana, have invented and discovered certain new and useful Improvements in Rule-Holding Slug-Forms for Linotype-Machines and Processes of Producing Same, of 10 which the following is a specification.

Our invention relates to rule holding slug forms for type slug casting machines and processes of producing same and its objects are to provide means whereby vertical rules 15 may be held securely in position in the form against displacement in a line perpendicular to the type faces; whereby means additional to the slugs for holding such rules are dispensed with; whereby any interruption 20 of the printing face by such extra means is avoided, and whereby the use of matrices for casting the holding means is avoided and such holding means may be inexpensively formed in the slugs themselves and in perfect alinement. 25

With these objects and others in view our invention is embodied in preferable form in the arrangement hereinafter described and illustrated, and in the process herein- 30 after set forth.

In the drawings, Figure 1 is a top plan view of a form of slugs showing several vertical rules mounted in place thereon; Fig. 2 is a vertical section showing the side 35 of one of the slugs in elevation and showing several rules in position thereon and with one of the line of rule receiving slots vacant, the rule being removed therefrom; Fig. 3, an enlarged detail perspective view 40 of part of the rule, and Fig. 4, an enlarged detail view in side elevation of one of the slugs, showing a rule in section.

Referring to the drawings, 1 indicates a 45 slug bearing a line of type faces 2. A vertical column of these slugs is employed, as is usual in type slug casting machines, to make up the complete table or form of slugs.

3 is a brass rule adapted to be disposed 50 vertically with respect to the column of slugs and the function of which is to provide means for printing a vertical ruling line such as may be employed to separate columns of figures, for instance. In the

drawings a plurality of these rules are 55 shown in connection with the column of slugs but only one may be employed or a greater number than those shown may be used if desired. The preferable form of this rule is indicated in Fig. 3, and in cross 60 section it is of an elongated substantially wedge-shaped form of a height sufficient to carry its outer surface to a level with the surface of the type faces and to project downwardly into a slot formed in the slug 65 below the level of the quad surface. The upper part of the rule is tapered off to bring the rule to a fine edge. Taking the usual height of the type and quad the height of the rule will be preferably 5/32 70 of an inch. The rule is preferably 1/16 of an inch wide at its bottom and 1/32 of an inch at the lower edge of the level of the top of the quad.

A slot 4 is sawed in such slug and the 75 upper edges of the slot is "quad high." The slot extends downwardly from the surface of the quad, preferably for a depth of 5/32 inches and is narrower at the top than at the bottom and is preferably dove-tailed 80 in shape, being approximately 1/16 inch wide at the bottom and 1/32 inch wide at the top of the slot. The quad surface is formed by that portion of the upper edge of the slug from which the base on which 85 the printing character is cast, projects. In producing these slots, a series of the slugs is arranged in vertical column to form the complete table or form and then a continuous line of dove-tailed slots is sawed 90 directly in the quad surfaces of the slugs. The table or form is then removed to the press for printing therefrom. By this method the dove-tailed slots are formed and retained in perfect alinement and castings 95 of the slugs to provide the rule-holding means by the use of special matrices is avoided.

After the line of slots has been sawed, the rule is placed therein by inserting the rule 100 into the slots at the end of the line and it is firmly held in the slots against escape in a line perpendicular to the face of the type, without further manipulation of the slugs or rule.

In addition to the advantages of obtaining 105 alinement and dispensing with the use of special matrices, our invention also possesses

the following advantages. It is impossible for the rule to pull out of a form in printing. Less than half the time consumed by other methods now in use is required in the 5 use of our invention to insert or remove the rules. The rule may be cut in labor saving lengths and can be used many times, thus eliminating the cost of a new rule for different jobs and the rule may be used on any 10 size of slug, leaded or solid, with type faces ranging from 4½ to 48 point. The continuous slot may be sawed for as great a length as 5" with one movement, thus saving time. This invention also saves time in enabling 15 revise corrections to be made readily as the rule can be removed and replaced easily.

The particular advantages of the process employed, in addition to that already referred to are that as compared with casting 20 special rule holding bodies or sawing or punching openings, the edges of which must be bent to secure the rule, it does not require two operations, nor a specially built machine 25 for casting the slugs. The slots are below quad high surface as compared with the present objectionable process of having the rule holding means projecting above the quad surface. Our method of sawing the 30 slots dispenses with the use of extra leads with slots or braces therein.

Having thus described our invention what we claim is:

1. A printing form having a plurality of 35 slugs bearing printing characters arranged with their adjacent faces in contact, said form having a continuous line of rule locking recesses formed in the bodies of the individual printing character slugs and between 40 the ends of the respective slugs and below the quad surfaces thereof, whereby the rule is locked to each slug through which it passes, in combination with a rule extending at right angles to the lengths of the slugs and 45 formed to engage said recesses, substantially as described.

2. A printing form having a plurality of

printing character slugs disposed face to face, said form having a continuous line of slots for holding the rule, each of said slots 50 being formed in the body of and between the ends of a printing character slug, said slots extending downwardly from the quad surfaces and below the same, and being narrower at their upper ends than at the 55 lower ends, in combination with a rule extending at right angles to the lengths of the slugs and formed complementarily to the slots and engaging the latter, substantially as described. 60

3. In combination with a printing form, a rule adapted to extend at right angles to the lengths of the slugs composing the form, in combination with a printing character bearing slug in said form, provided with a 65 rule locking recess in the body of the slug between the ends thereof, and extending downwardly from the quad surface of the slug, said recess being formed to retain the rule against withdrawal in a line perpendicular to the printing face, but permitting the insertion of the rule through the side of the slug, substantially as described. 70

4. A printing form having a plurality of slugs bearing printing characters, said slugs 75 being provided with dove-tailed slots formed in the bodies of the slugs and extending from and below the quad surfaces thereof, and between the ends of the slugs, in combination with a vertical rule complementarily formed to fit said slots, the latter being alined in a line at right angles 80 to the lengths of the slugs, substantially as described.

In witness whereof, we have hereunto set 85 our hands and seals at Indianapolis, Indiana, this 17th day of May A. D., nineteen hundred and thirteen.
